J. F. WINKLER

PRESSURE ELECTRIC SWITCH

Filed Nov. 16, 1921

Inventor—
Joseph F. Winkler
by his Attorneys—
Fowson & Fowson

UNITED STATES PATENT OFFICE.

JOSEPH F. WINKLER, OF PHILADELPHIA, PENNSYLVANIA.

PRESSURE ELECTRIC SWITCH.

Application filed November 16, 1921. Serial No. 515,584.

One object of my invention is to provide a pressure controlled electric switch with novel means whereby the movable contact of said switch shall be maintained in its closed position until it is automatically tripped by reason of fluid or gaseous pressure rising above a predetermined point, and the invention further contemplates novel means whereby the resetting of said switch is prevented until the pressure of the fluid to be controlled has fallen to a second predetermined point below that at which tripping of said switch was caused.

Another object of my invention is to provide novel means for controlling the automatic operation of an electric switch which shall be of such a nature as not to be affected by abnormal vibration and in which the arrangement of parts is such that it cannot open except under predetermined conditions.

These objects and other advantageous ends I attain as hereinafter set forth, reference being had to the accompanying drawings, in which,

Fig. 1 is a front elevation of one embodiment of my invention; and

Fig. 2 is a side elevation of the apparatus shown in Fig. 1.

In the above drawings, 1 represents a suitable dust-proof containing casing, within which is mounted a Bourdon tube connected through a pipe 3 to the fluid containing system whose operation is to be controlled. The closed end of the tube 2 is provided with a head 4 pivoted by a pin 5 to one end of a lever 6. Projecting from this lever adjacent its pivot 5 is a downwardly extending arm 7 having connected to it one end of a spring 8, whose opposite end is fixed to a post 9 projecting from the back of the casing 1. Operative on the opposite side of said lever from the arm 7 is an adjustable fulcrum screw 10 for setting the device as hereafter described. The free end of the lever arm 6 extends between the branches of a fork 11 projecting from a trigger lever 12 fulcrumed on a pin 13 fixed to the back of the casing and having a downwardly projecting arm 14 and a hooked head 15; the arrangement being such that the movement of the lever 6 tends to operate the trigger lever 12 on its pivot pin 13.

Rotatably mounted on this pin is a disc 16 having a radially formed slot 17 and provided with a projecting pin 18 positioned to cooperate with the arm 14 of the lever 12

under certain conditions. This disc 16 at all times tends to rotate in a counter clockwise direction on its supporting pin or spindle 13 under the action of a spring 19 connected to its pin 18 and hooked to the trigger lever 12.

Slidably mounted in the casing structure 1 is a manually operative setting plunger 20 in the form of a push rod normally maintained in an elevated position by a spring 21 operative between its head 20^a and a guide bearing 22 carried by the casing. The lower end of this plunger rod carries a U-shaped yoke 23 between whose arms is journaled a roller 23^a capable of engaging with the trigger lever 15 to hold the plunger rod 20 in its depressed position against the action of its spring 21. Said roller is also capable of entering the slot 17 of the disc 16 when this latter is in a predetermined position.

Carried by the plunger rod 20 is the movable contact 24 of an electric switch which in the present instance is of the multiple contact type, having a pair of lower fixed contacts 25-25 and a pair of upper fixed contacts 26-26. When said plunger 20 has been so far depressed that its roller is engaged by the hook or trigger 15, the movable contact 24 engages the lower contacts 25-25, but when said trigger disengages said roller, the spring 21 acts to elevate the plunger rod to its upper position in which the movable contact 24 engages the upper fixed contacts 26-26.

Under conditions of use as long as the pressure in the Bourdon tube remains below a predetermined amount, it is possible to depress the plunger rod 20 so as to cause its roller 23^a to engage and be held down by the trigger 15 so that the switch contacts 25-25 are engaged by the contact 24. When however, the pressure in said tube rises above the predetermined point, the lever 6, turning on the fulcrum screw 10, turns the lever 12 on its pin 13 and disengages the hook 15 from the roller carried by the plunger rod 20, thereby permitting the plunger rod to rise, disengaging the contact 24 from the switch contacts 25-25 and causing said contact to connect the contacts 26-26.

At the same time this turning of the lever 12 and the resulting upward movement of the roller out of the slot 17 leaves the disc 16 free to be turned in a counter-

clockwise direction on its spindle 13 under the action of the spring 19, thus causing the pin 18 to follow the lever 12 until it engages the arm 14 thereof. The slot 17 is now out of the line of movement of the roller, so that even though the plunger rod 20 be moved downwardly, the switch cannot be moved into such a position as to cause the contact 24 to engage the contacts 25—25.

If now the pressure in the system to which the tube 2 is connected falls to the predetermined point, the lever 6 is moved under the action of the spring 8 so that the trigger lever 12 is turned on its spindle 13 in a clockwise direction, whereupon its arm 14 engages the pin 18 and restores the disc 16 to such a position that the roller on the plunger rod may again be moved into the slot 17. Under these conditions, when said plunger rod is depressed, the roller acts on the head of the trigger 15, displacing this and moving under it into its engaging position shown in the drawings, thus holding the plunger 20 down and retaining the switch contact 24 in engagement with the lower fixed contacts 25—25.

I claim:

1. The combination with an electric switch of a push rod carrying the movable contact of said switch and having a projecting part; a trigger lever movable in response to fluid pressure variations in a system to be controlled and positioned to engage the projection to normally hold the push rod with the switch closed; with a rotary member automatically movable into position to prevent resetting of the push rod and closure of the switch after said rod has been disengaged by the trigger lever.
2. The combination with an electric switch of a push rod carrying the movable contact of said switch and having a projecting part; a trigger lever movable in response to fluid pressure variations in a system to be controlled and positioned to engage the projection to normally hold the push rod with the switch closed; a rotary member automatically movable into position to prevent resetting of the push rod and closure of the switch after said rod has been disen-

gaged by the trigger lever with means for rotating said member into position to permit resetting of the push rod when the pressure has fallen to a predetermined point.

3. The combination with an electric switch of a push rod carrying the movable contact of said switch and having a projecting part; a pressure responsive element; a trigger lever actuated by said element and positioned to engage the projection to hold the push rod with the switch closed as long as the pressure acting on said element is below a predetermined point; a rotary member having a slot positioned to receive the projecting part of the push rod when it is engaged by the trigger lever; and means for causing rotation of said member when said projecting part moves out of its slot to prevent resetting of the push rod and closure of the switch. 70

4. The combination with an electric switch of a push rod carrying the movable contact of said switch and having a projecting part; a pressure responsive element; a trigger lever actuated by said element and positioned to engage the projection to hold the push rod with the switch closed as long as the pressure acting on said element is below a predetermined point; a rotary member having a slot positioned to receive the projecting part of the push rod when it is engaged by the trigger lever; and means for causing rotation of said member when said projecting part moves out of its slot, said trigger lever including a part for restoring the rotary member to a position to receive said projecting part when the pressure falls to a predetermined point. 80

5. The combination with an electric switch of a pressure actuated member; means controlled by said member for holding the switch closed until the pressure rises above a predetermined point; with means for preventing closure of the switch until the pressure falls below another predetermined point, said last mentioned means being actuated in one direction by said first mentioned means. 90

JOSEPH F. WINKLER.
